UNITED STATES PATENT OFFICE

HANS G. GUSTAFSSON, OF CHICAGO, ILLINOIS, ASSIGNOR TO WESTERN ELECTRIC COMPANY, INCORPORATED, OF NEW YORK, N. Y., A CORPORATION OF NEW YORK

GUARDING DEVICE

Application filed April 24, 1930. Serial No. 446,949.

This invention relates to a guarding device, and more particularly to a guarding device for a die casting machine.

An object of this invention is to provide a simple and efficient guarding device for covering movable parts of a machine.

In accordance with this object one embodiment of the invention comprises a hood which is hinged to a support secured to the frame of the machine of which the movable parts are to be guarded. Rocker levers mounted on a shaft journaled in the support engage projecting portions of the hood, and are rotated by a connecting rod linked to a rocker arm secured to a power driven shaft of the machine to lower and raise the hood over the moving parts thereof.

A clear understanding of the invention will be had from the following description when taken in connection with the accompanying drawings, wherein

Fig. 1 is a side view of a die casting machine with the guarding device attached;

Fig. 2 is an enlarged side view of the guarding device;

Fig. 3 is a plan view of the guarding device with a part thereof broken away and shown in section;

Fig. 4 is a fragmentary detail view of the hinging structure for the guarding device, taken on the line 4-4 of Fig. 3, and

Fig. 5 is a fragmentary cross-sectional view of the hinging structure taken on the line 5-5 of Fig. 4.

Referring now to the drawings in which like reference numerals designate similar parts throughout the several views, there is disclosed a three-sided hood 10 which is designed to cover or guard the stationary and movable dies of the die casting machine shown in Fig. 1 when the dies are brought together for the casting operation. This hood consists principally of two vertical side sheets of metal 11-11 and a top horizontal sheet 12, which sheets are supported by framework consisting of vertical angle members 13-13 (Figs. 2, 4, and 5) provided on each side of the hood, and horizontal angle members 14-14 (Figs. 3 and 5) forming the frame of the hood at the top, the ends of these

angle members having their flanges beveled at 45° to their axes and thus being dovetailed in or abutting each other as shown particularly in Figs. 2 and 3. The framework and sheets are preferably secured together by welding. A pair of vertical metal sheets or strips 15-15 are welded to the edges of the left hand side of the hood 10 to fit over the movable die of the casting machine. A pair of studs 17-17 extend through each side of the hood 10 and are welded thereto and to a pair of triangular reinforcing members 18-18 (Figs. 2 and 5), which are welded adjacent the edges of the angle members 13 and 14 and to the sheets 11-11. Flat metal straps 21-21 (Fig. 2) join the lower ends of the vertical angle members 13-13 and are welded to the vertical sheets 11-11 for reinforcing their lower edges. A pair of spaced hinge straps 20-20 are welded to the right hand edge of the top horizontal sheet 12.

A hinging support for the hood 10 is provided, comprising a pair of side plates 24-24 which are secured at the bottom by bolts 25-25 to the frame of the die casting machine, and the inner surfaces of the plates 24-24 have a framework welded thereto which consists of a pair of vertical angle members 26-26 (Figs. 2 and 5) secured to each side plate, and which are joined at their tops to a transverse angle member 27 (Figs. 2 and 5). A metal sheet 28 (Figs. 2 and 4) which serves to reinforce the angular framework comprising the angle members 26 and 27 is secured by screws 30 to this angular framework. The screws 30 arranged across the horizontal arm of the U-shaped sheet 28 also secure to the frame work an offset plate 31 (Figs. 2, 4 and 5) to which is fixed by means of a pair of bolts 32-32 (Figs. 3, 4 and 5) the upper end of a stationary die plate 29 of the die casting machine, (shown in outline by dot and dash lines) the lower end of the die plate being supported on the frame work of the machine. A pair of spaced hinge straps 33-33 are welded to the transverse angle member 27 and to a pair of slanting angle members 34-34 which are welded to the right hand beveled edges of the plates 24-24 which cooperate with a lid 35 which

may be lowered over the machine. A cross rod or shaft 36 extends through and is freely journaled within the loops in the pair of hinge straps 33-33 secured to this angular framework of the plates 24-24 and through the loops in the pair of hinge straps 20-20 secured to the edges of the hood 10. Four bolts 37-37 (Figs. 2 and 4) secure the lower portions of the metal sheet 28 to the die plate 29, and extensions 38-38 (Fig. 2) from each side of this sheet lap around underneath a pair of side lugs 39-39 (Fig. 2) extending outwardly from the stationary die plate 29, which extensions are screwed to the plates 24-24 as shown in Fig. 2.

For swinging the hood 10 there is provided a pair of rocker levers 40-40 which are keyed to the ends of the rod 36 and engage the lower surfaces of the studs 17-17, and one of the levers 40 has an integral arm 41 which is pivoted to a link 42. A connecting rod 43 is threaded into the link 42 and into a second lower link 44 which is pivoted to a crank 45 which is in turn keyed to a cross-shaft 46 that actuates the charging pot or pneumatic pump (not shown) of the casting machine. The cross-shaft 46 may be actuated by any suitable connection with the movable die plate of the machine and is here shown as actuated by a segmental gear 47 which is covered by a guard 48 which slidably supports a rack 49 which forms a part of a connecting rod 50 which is pivoted at 51 to the movable die plate of the machine.

In the operation of the aforescribed hood and actuating structure the hood 10 is, of course, down and covering the movable and stationary dies when the two dies are engaging each other for casting purposes, and when the movable die is moved away from the stationary die the shaft 46 is rotated in a clockwise sense by means of the connecting rod 50 and rack and gear 49 and 47. This rotation moves the connecting rod 43 downwardly and rotates the levers 40-40 in a clockwise sense, causing them to bear against the lugs 17-17 to swing the hood 10 about the hinge straps 20-20 to the dot and dash position shown in Fig. 2, whereupon the parts cast are removed from the dies. When the dies are again moved into engagement with each other the connecting rod 43 is moved upwardly, due to the actuation of the rack and gear 49 and 47, which are moved by the connecting rod 50 connected at 51 to the movable die, to rock the levers 40-40 in a counterclockwise sense. The lugs 17-17 resting on the levers 40-40 then allow the hood to return to its closed position to cover the engaged movable and stationary dies. The operator is then protected by the hood from any possibility of being injured by escaping metal, and it will be noted that the hood is automatically low-

ered without the necessity for any attention on the part of the operator.

Although the invention has been described and illustrated as to one specific embodiment, it will, of course, be understood that the invention is not to be limited thereto, but is to be limited only by the scope of the appended claims.

What is claimed is:

1. In a guarding device, supporting means secured to a machine to be guarded, means for covering parts of the machine to be guarded while the parts are in an operative position, means for horizontally hinging the covering means to the supporting means, rocker means attached to each side of the covering means, means common to the rocker means for swinging the covering means, rocker means attached to a shaft of the machine, and means connecting the last mentioned rocker means with the means common to the first mentioned rocker means to actuate the first mentioned rocker means.

2. In a guarding device, supporting means secured to a machine to be guarded, a hood for covering parts of the machine to be guarded while the parts are in an operative position, means for horizontally hinging the hood to the supporting means, rocker levers attached to the supporting means for swinging the hood thereabout, a link connected to one of said rocker levers, a connecting rod secured at one end to the link, a link secured to the other end of the connecting rod, and a rocker arm connected to the last mentioned link and secured to a shaft of the machine for swinging the hood over the parts.

3. In a guarding device for a die casting machine, a rocker arm secured to a charging pot rotating shaft of the machine, a connecting rod pivotally secured to the rocker arm, a supporting means secured to the casting machine, a cross-shaft horizontally journaled in the supporting means, a rocker arm secured to the cross-shaft and pivotally attached to the connecting rod for rotating the cross-shaft, a three-sided hood freely suspended at one edge from the cross-shaft, a pair of lugs extending outwardly from the hood, and a pair of rocker levers secured to the cross-shaft for engaging the lugs to rotate the hood about the cross-shaft.

In witness whereof, I hereunto subscribe my name this 14th day of April A. D., 1930.

HANS G. GUSTAFSSON.
